UNITED STATES PATENT OFFICE.

JULIUS BAER, OF NEW YORK, N. Y.

HAIR-NET.

961,476.

Specification of Letters Patent. Patented June 14, 1910.

Application filed February 8, 1910. Serial No. 542,659.

To all whom it may concern:

Be it known that I, JULIUS BAER, a citizen of the United States, residing at New York city, county and State of New York, 5 have invented new and useful Improvements in Hair-Nets, of which the following is a specification.

This invention relates to a hair net of novel construction which effectively protects 10 the hair from disarrangement, is of superior strength and may be readily applied.

The accompanying drawing represents a perspective view of my improved hair net.

Hair nets, as now generally made, are 15 exceedingly fragile, being composed of human hair or of thin silk threads, so as to be practically invisible when worn. Thus, these nets are very liable to tear, not only by the pressure of the head dressing, but 20 also by manipulation and by the hair pins used for holding them in position. By my invention, the net will be self-sustaining and will be so reinforced at its most vulnerable points, that its life is considerably prolonged 25 without sacrificing its invisible character.

I propose to form the net in the shape of a bag, which may be projected over the coiffure, to completely inclose the same. This bag is composed of three interknotted or in- 30 terwoven sections, each of which has its own characteristics. The cup-shaped crown-section 1, which must sustain the main brunt of the pressure, is closely netted, being composed of small meshes which are of superior 35 strength, but of comparatively limited elasticity. The zone-shaped main section 2, which covers the bulk of the coiffure is composed of meshes which are considerably larger than those of section 1, so that the

net is here practically invisible and of su- 40 perior elasticity, so that it will readily conform itself to the peculiar style of dressing. As this portion of the net is not subjected to any severe strain, invisibility and elastic- 45 ity are here obtained at the expense of 45 strength.

The lower section 3 of the net, which constitutes the rim of the bag, has for its object to exercise a contractile effect upon the edge of the bag, so that the latter firmly 50 grips the hair and renders the bag self-sus- taining. To this effect this rim-section is also made of meshes which are considerably 55 smaller than those of section 2, and which, in addition to their tendency of drawing the mouth of the bag together, have the additional function of forming a reinforcement at the rim, which, of course, is subjected to 60 severe strain, especially when the net is being put on.

If desired, an endless elastic cord 4 may be drawn through the net at a considerable distance from its edge, preferably at or near the junction of sections 1 and 2. This cord will assist the contractile rim-section 3 in 65 holding the net in position, without disfiguring the face, by extending over the fore- 70 head of the wearer.

I claim:

A hair net made of bag like form and com- 70 prising a small meshed cap-like apex, an annular large meshed central section, and a small meshed annular contractile rim.

JULIUS BAER.
